UNITED STATES PATENT OFFICE.

JAMES FRANKLIN KING, OF MILWAUKEE, WISCONSIN.

BATH APPARATUS.

1,066,121.

Specification of Letters Patent.

Patented July 1, 1913.

Application filed March 23, 1912. Serial No. 685,897.

To all whom it may concern:

Be it known that I, JAMES FRANKLIN KING, a citizen of the United States, and resident of Milwaukee, in the county of Milwaukee and State of Wisconsin, have invented certain new and useful Improvements in Bath Apparatus; and I do hereby declare that the following is a full, clear, and exact description thereof.

10 My invention consists in what is herein particularly set forth with reference to the accompanying drawings and pointed out in the claim of this specification, its object being to provide simple, economical and 15 portable sanitary bathing apparatus designed to inclose the person of a bather and with which aeriform, liquid or aerated liquid baths, medicated or otherwise may be administered by the bather personally or by an 20 attendant, said apparatus being for home, hospital, sanatorium and travelers' use, and serving where the ordinary bath conveniences are not available.

Figure 1 of the drawings represents a 25 front elevation of bathing apparatus in accordance with my invention partly broken away and enveloping the person of a bather; Fig. 2, a sectional view of a detail of the apparatus illustrating how the same is closed 30 airtight on the bather; Fig. 3, an elevation of a pad-collar constituting part of said apparatus, and Fig. 4, a perspective view of the open upper end of a bag constituting another part of the apparatus.

35 Referring by numerals to the drawings, 5 indicates a bag made from any suitable flexible waterproof material and provided at its upper end with a casing 6 for a drawstring 7, the ends of the drawstring being within 40 the bag. Designed to be partially inclosed by the bag, at the upper end of the same, is a pad-collar 8 for the neck of the bather, and by means of the drawstring, said end of the bag is gathered or Shirred airtight on the 45 collar without discomfort to said bather. Wool has been found preferable as a stuffing because of its adaptability to conform to the person of the wearer with reference to obtaining an air-tight fit of the bag upon the 50 bather, and because of its comfort, for the collar, but any suitable material may be employed, and said collar may be separable

from the bag, as herein shown, or attached thereto as found most convenient or desirable in practice.

55 The front of the bag, adjacent to its upper end, is provided with an inflating attachment of any suitable construction, the one shown being a plate 9 having an outwardly extending check-valve nozzle 10 the plate 60 being secured upon the inside of said bag by a backing strip 11 attached thereto or otherwise as may be found desirable.

The bather being in the bag, the collar is positioned and the drawstring operated to 65 close said bag airtight on said collar, after which air, steam or other aeriform fluid may be injected into said bag by an attendant, said fluid being medicated if desired. Or previous to enveloping the bather, as above 70 specified, the bag may be partially filled with water or other liquid with which to bathe, as shown at 12 in Fig. 1, and if desirable the bather may inflate said bag by blowing therein through the aforesaid nozzle. 75 To thus inflate the bag, a portion of the same is lifted by the bather from within to bring the nozzle to his mouth. By alternate crouching and rising in the bag or by rolling with the same upon a bed or floor on the 80 part of the bather, or by manipulations of an attendant, the liquid in said bag, aerated or otherwise may be made to surge in simulation of sea waves and thus afford gratification to said bather. By employing hot water 85 and compressed air in the bag, the actions of the bather or the manipulation of an attendant, as aforesaid, will produce an accumulation of steam and gas in said bag and thus enhance the pleasure of the bath. 90

95 Soap, and other toilet conveniences may be taken into the bag for the use of the bather, and after a bath said bag may be readily drained of its liquid contents and thoroughly cleaned.

The length of the collar 8 may be such as to permit of the same serving as a waistband when it is only desirable to bathe below the waist in which case the drawstring is manipulated from outside the bag.

I claim:

A bath apparatus comprising a bag of suitable flexible waterproof material, an inflating attachment with which the front of

the bag is provided adjacent to its upper end, and means for closing said bag air-tight about the neck of a bather therein, the position of the inflating attachment being such that it may be brought to the mouth of said bather by lifting from within said bag.

In testimony that I claim the foregoing I

have hereunto set my hand at Milwaukee, in the county of Milwaukee and State of Wisconsin, in the presence of two witnesses.

J. FRANK KING.
